UNITED STATES PATENT OFFICE.

WILLIAM C. URBAN, OF GRANITE CITY, ILLINOIS, ASSIGNOR OF ONE-HALF TO HOYT METAL COMPANY, OF ST. LOUIS, MISSOURI, A CORPORATION.

CASTING APPARATUS.

1,110,659.

Specification of Letters Patent. Patented Sept. 15, 1914.

Application filed February 18, 1913. Serial No. 748,097.

To all whom it may concern:

Be it known that I, WILLIAM C. URBAN, a citizen of the United States of America, residing at Granite City, in the county of 5 Madison and State of Illinois, have invented certain new and useful Improvements in Casting Apparatus, of which the following is a full, clear, and exact description, reference being had to the accompanying drawings, forming a part of this specification.

My invention relates to an apparatus for making die castings and has for its object the production of a very efficient means for handling molten material whereby the dross 15 which accumulates at the surface of the material in the melting pot is prevented from entering the die or mold. Also, to provide an apparatus for melting metal and forcing the molten metal into a die by air pressure, 20 without liability of injuring the operator.

Another object is to provide means for so confining the molten metal that it will not cool to any appreciable extent in flowing from the melting pot to the die or mold.

25 Figure I is a vertical section, partly in elevation, of my casting apparatus. Fig. II is a top or plan view, partly in section. Fig. III is a view similar to Fig. I, showing the valves and valve operating devices in 30 different positions.

In the accompanying drawings:—1 designates upright posts connected at their upper ends by a cross bar 2. Hanger rods 3, secured to the cross bar 2, support a receptacle 35 4. This receptacle is preferably a melting pot, having an outer or primary compartment A, open at the top for the reception of metal to be melted, and an inner or secondary compartment B, in the form of a tube 40 adapted to receive molten metal from the outer compartment.

45 5 designates an admission valve for opening and closing communication between said inner and outer compartments. The valve 5 and the passageway controlled thereby is located near the bottom of the melting pot, so that the dross at the surface of the material in the compartment A cannot enter the inner compartment B. The inner compartment 50 is provided with a closure at its lower end, said closure having an opening 6 through which the molten metal may be discharged into a die 7.

55 8 designates a valve for opening and closing the discharge opening 6, said valve hav-

ing a long stem 9 passing through the closure at the upper end of the compartment B and extending above the transverse frame bar 10 at the upper end of the apparatus. A compression spring 11 for forcing the valve 60 8 onto its seat surrounds the valve stem 9, and is arranged between the bar 10 and a collar 12 on said stem. The means for opening the discharge valve 8 comprises an operating handle 13, in the form of a lever 65 pivoted at 14, and carrying a swiveled device 15 having a lip 16, which lies below the collar 12 and surrounds the valve stem 9. When the lever 13 is elevated, it carries the swiveled device 16 upwardly into engagement with the collar 12 and, as said collar is rigidly secured to the valve stem 9, a continued movement of the lever will open the valve 8 and allow the molten metal to flow 70 into the die 7.

75 Air under pressure is admitted to the upper portion of the chamber B through a pipe 17, the admission of air being controlled by an air valve 18 having an operating handle 19 connected by a link 20 to the lever 13. 80 When the lever 13 is rocked upwardly to open the discharge valve 8, the air valve 18 rocks from the position shown in Fig. II, thereby allowing the air under pressure to enter the inner compartment B, with the result of forcing the molten metal through the discharge opening 6 and into the die 7. To cause the air valve 18 to open and admit the compressed air to the compartment B before the discharge valve 8 opens, the swiveled device 15 is designed so that its lip 16 lies some distance below the collar 12 on the valve rod 9 when both of said valves are 85 closed. While the lip 16 is moving toward the collar 12, the air valve 18 opens and 90 thereafter said lip strikes the collar 12, and continues its upward movement, with the result of opening the discharge valve 8 and permitting the air under pressure to force 95 the molten metal through the discharge opening 6.

100 The inner compartment B may be supplied with molten metal by opening the admission valve 5, said valve being controlled by a handle 22 secured to the valve stem 23. 105 To permit the escape of air from the inner compartment B while it is receiving molten metal from the outer compartment, the casting of the air valve 18 is provided with a vent 24, (Fig. I), and the valve 18 is pro- 110

vided with an auxiliary port 25, through which air may pass from the inner compartment to the main port in valve 18, and thereafter escape through the vent 24.

5 If the air valve 18 were accidentally opened to admit air under pressure to the inner compartment B while the admission valve is open, it will be noted that the molten metal would be forced through the valve 5 and discharged into the atmosphere through the open upper end of the outer compartment A. To positively prevent such accidental opening of the air valve 18, the valve stem 23 secured to the admission valve 5 is provided with a stop arm 26 which lies directly over the lever 13 when the admission valve 5 is open, (see Figs. I and II.) This stop arm is located to prevent the lever 13 from being elevated, thereby preventing the air valve 18 and discharge valve 8 from being opened while the admission valve 5 occupies its open position. When the admission valve 5 is closed, the stop arm 26 is located in the position shown by dotted lines, (Fig. II), where it does not in any way interfere with the operation of the lever 13.

The process of making castings described in connection with my casting apparatus, is not claimed herein, the said process being described and claimed in an application for patent filed by me February 13, 1913, Serial No. 748,096.

I claim:

1. A casting apparatus comprising a melting pot, a pressure tube adapted to communicate with said melting pot, said tube having a closure at its upper end and having its lower end secured to the middle portion of the bottom of said melting pot, means for opening and closing communication between said tube and melting pot, a closure for the bottom of said tube located at the bottom of said melting pot, said closure having a discharge port through which molten metal may be discharged downwardly from said tube and melting pot, a vertically movable discharge valve at the bottom of said tube

for opening and closing said discharge port, a valve stem secured to said valve and extending through the closure at the upper end 50 of said tube, a spring tending to hold said valve upon its seat, and means for operating said valve stem.

2. A casting apparatus, comprising a melting pot, a pressure tube arranged within and adapted to communicate with said melting pot, an admission valve for opening and closing communication between said pressure tube and melting pot, the apparatus being provided with a discharge port through 60 which molten metal may be discharged from said pressure tube into a die, a discharge valve adapted to open and close said discharge port, said discharge valve being separate from and having no direct connection 65 with said admission valve, and the admission valve being operable to open and close communication between said pressure tube and melting pot while the discharge valve is closed.

3. A casting apparatus, comprising a melting pot, a pressure tube arranged within and adapted to communicate with said melting pot, an admission valve for opening and closing communication between said pressure tube and melting pot, the apparatus being provided with a discharge port through 75 which molten metal may be discharged from said pressure tube into a die, a discharge valve adapted to open and close said discharge port, said discharge valve being separate from and having no direct connection 80 with said admission valve, and the admission valve being operable to open and close communication between said pressure tube and melting pot while the discharge valve is closed; combined with means for automatically locking said discharge valve in its closed position while the admission valve is in its open position.

W. C. URBAN.
